CARRYING HANDLE FOR GARMENT HANGERS

Nat B. Gentry, 12553 W. Alameda,
Denver, Colo. 80228

Filed Oct. 12, 1971, Ser. No. 188,657

Term of patent 14 years

Int. Cl. D8—06

U.S. Cl. D8—154

FIG. 1.

FIG. 2.

FIG. 3.

FIG. 4.

FIG. 1 is a front view in elevation of the carrying case for garment hangers showing my new design;

FIG. 2 is a right side elevation thereof;

FIG. 3 is a top plan view thereof; and

FIG. 4 is a bottom plan view.

The rear elevation is identical to the front elevation and the left side elevation is identical to the right side elevation.

I claim:

The ornamental design for a carrying handle for garment hangers, as shown and described.
